UNITED STATES PATENT OFFICE.

JOHN L. DRESSLER, OF NEW YORK, N. Y.

CARBURETER.

1,214,767.

Specification of Letters Patent. Patented Feb. 6, 1917.

Application filed March 8, 1913. Serial No. 752,891.

To all whom it may concern:

Be it known that I, JOHN L. DRESSLER, a citizen of the United States of America, residing in New York, in the borough of the Bronx, county and State of New York, have invented certain new and useful Improvements in Carbureters for Gasolene-Engines, of which the following is a specification.

This invention relates to an improved carbureter for gasolene-engines by which a regular supply of fuel in vapor form is supplied and then mixed with the required quantity of air for combustion, and by which the supply of gasolene or other fuel to the carbureter is controlled in a very effective manner, without being affected by the motions of the automobile to which the engine is applied.

The invention consists of a carbureter for gasolene-engines which comprises a fuel-receptacle, a float in the same, a fuel supply-pipe, a valve for the same operated by said float, a fuel suction-pipe provided with a needle-valve, an air suction-pipe by which the fuel is vaporized, a mixing-chamber, and a spring-regulated air admission-valve for supplying the required quantity of air necessary for combustion to the mixing-chamber and to the cylinders of the engine.

The invention consists further of certain details of construction which will be fully described hereinafter and finally pointed out in the claims.

In the accompanying drawings, Figure 1 is a vertical sectional view of my improved carbureter, Fig. 2 is a plan view, partly in horizontal section on the line 6—6 of Fig. 1, and Fig. 3 is a vertical transverse section on the line 7—7 of Fig. 2.

Similar reference characters indicate corresponding parts throughout the several figures of the drawings.

Referring to the drawings, *a* represents a cylindrical receptacle for the gasolene, which is connected to the gasolene tank by a suitable supply pipe (not shown). The top and bottom plates of the gasolene receptacle *a* are connected by a central tubular screw-post *g* through which atomizing air is supplied as hereinafter more fully pointed out, said port being held in place by a screw nut *a*⁴ at the lower end thereof. On the gasolene receptacle *a* is supported a cylindrical mixing chamber *b*, which is connected to the manifold *m*¹ by a horizontal supply pipe *b*², the manifold extending to the cylinder of the

engine in the well known manner. The receptacle *a* is provided with an outlet cock *a*¹ on its bottom plate for drawing off the fuel when the carbureter is not required for use. In the gasolene receptacle is located an annular float *f* which is made of a ring of cork, a hollow ring of copper or other material, and which float is connected by upright arms *f*¹ with the ends *f*² of a lever (not shown) which controls the supplying of gasolene to the receptacle in the well known manner. The gasolene in the receptacle *a* is kept above the level of the gasolene suction pipe *d*, which extends from the top plate of the receptacle downwardly into the gasolene therein. The suction pipe *d* is supported in a block *d*¹, screwed into the top plate of the receptacle *a*, and extended downwardly to a point at some distance from the bottom of the same, as shown in Fig. 1. The upper end of the suction pipe *d* communicates with a horizontally disposed gasolene delivery tube *d*⁶, which passes through a central bore *d*² and a bore *d*⁸ in the block *d*¹, disposed at the upper end of the pipe *g*, the bore *d*⁸ being spaced from the pipe *d*⁶. The opening of the tube *d*⁶ is opened and closed by a needle-valve *d*³ provided with a hand wheel *d*⁴ at its outer end. The gasolene delivery pipe *d*⁶ is surrounded by a pipe *d*⁷, which is provided with a gage cap so that the mixture of air and gasolene vapors are evenly distributed to the mixing chamber *b*. A valve-casing *c* is provided on the mixing chamber *b* in axial alignment with the fuel receptacle *a*, and which is open at its lower end and closed by an air admission-valve *c*¹ mounted on a central stem *c*² that passes vertically through the casing *c*, and that can be adjusted higher and lower by means of its threaded upper portion and a screw nut *c*³. A helical spring *s* is interposed between the valve *c*¹ and a collar *c*⁴ on the stem *c*², this tension of the spring being regulated by the adjustment of the valve-stem *c*². In the connecting pipe *b*² is arranged a throttle-valve *h*, which is placed into open or closed position by means of a crank-arm *h*¹ applied to its center pivot *h*² and a lever-rod *h*³, the position of the throttle-valve when in entirely open position being obtained by a projection *b*⁴ abutting on a screw-stop *b*⁵ on the top plate of the mixing chamber *b*. By more or less opening the throttle valve *h*, the quantity of explosive fuel and air mixture drawn in by the suction of the engine according to the speed

of the same. When the suction ceases, the gasolene which has been drawn upwardly in the tube d , falls back to its former level leaving a supply of atomized gasolene in the 5 suction pipe or walled space d , which supply will be further increased by the atomization in the pipe d so that there will be a supply of vapor before the next suction. Since the air tube g communicates with the bore d^2 , 10 this walled space is not directly in the path of the entering air current, which sweeps along the vapors by its aspirating action.

A cam i on the spindle of the throttle-valve by its movement reciprocates a rod i^1 15 mounted in a projection k , provided on the casing of the chamber b , and a projecting member k^1 secured to a tubular portion k^2 of the casing b , which slidably supports the needle valve casing b^6 . The rod i^1 is formed 20 in two pieces, and is adjustable by means of a coupling member k^5 engaging the threaded and adjacent ends of the two pieces forming the rod. A forked lever i^2 pivotally mounted in an extension k^4 of the supporting member k^1 contacts at one end with the end of 25 the rod d^1 , and at its forked end engages a sleeve k^5 rigidly secured to the needle valve casing b^6 , a spring b^7 being disposed between the sleeve and the end of the tubular support k^2 of the valve casing. The needle 30 valve h^5 is threaded, and by movement of the hand-wheel h^4 at the end thereof, may be adjusted independently of the throttle valve. The periphery of the hand wheel is 35 graduated by serrations, and an indicator i^3 extends over the same, engages between the serrations (as clearly shown in Fig. 1) so that the needle valve may be adjusted and the supply of gasolene regulated with great 40 exactness. The connection between the cam, the throttle valve and the needle valve casing is thus positive and there is no play between the parts as distinguished from connections maintained by the use of springs and other 45 yielding means.

The operation of my improved carbureter is as follows: The level of the fuel in the receptacle is regulated by the float, so that a regular supply of fuel in the receptacle is 50 kept up. By the turning of the fly wheel of the engine a suction is exerted in the carbureter, so that the gasolene is drawn through the pipe d , and atomized by the suction of the air drawn in through the pipe g after 55 opening the needle valve to the required degree. The mixture of air and vapor is then delivered into the mixing chamber, and there mixed with the additional quantity of air which is necessary to form the explosive 60 mixture, the latter being then drawn through the manifold m^1 into the cylinder of the engine. In order to regulate the quantity of the mixture supplied to the engine cylinder, the throttle valve is operated, 65 which through the cam i moves the rod i^1 ,

which in turn swings the forked lever i^2 , causing the needle valve to be moved in proportion to the movement of the throttle. By turning the hand-wheel h^4 , beneath the indicator i^3 the valve may be very accurately 70 adjusted independently of the throttle.

I have illustrated a preferred and satisfactory form of my invention, but it is obvious that changes may be made therein within the spirit and scope thereof as defined in the appended claims. 75

I claim:

1. In a carbureter, an outlet pipe for said carbureter, a revoluble throttle valve in said outlet pipe, a revoluble spindle in said outlet pipe, said throttle valve being mounted on said spindle, means on one end of said spindle for turning said throttle valve, a cam on the other end of said spindle, and adapted to be revolved therewith, a fuel pipe 80 for said carbureter, a valve for said fuel pipe comprising a slidable non-rotatable interiorly threaded valve casing, a threaded valve stem slidably engaging said threaded valve casing, and controlling the opening of 85 said fuel pipe, a hand wheel on said valve stem, and a pivoted forked lever engaging at its forked end said valve casing, a reciprocating rod disposed between the opposite end of said lever and said cam, and having 90 contacting engagement therewith, and a spring on said valve casing adapted to maintain engagement of said cam, rod and forked lever, whereby the movement of said cam proportionately reciprocates said valve casing 95 and said valve stem, said valve stem adapted to be rotatably moved independently of said casing by movement of said hand wheel.

2. In a carbureter, an outlet pipe for said carbureter, a revoluble throttle valve in said outlet pipe, a revoluble spindle in said outlet pipe, said throttle valve being mounted on said spindle, means on one end of said spindle for turning said throttle valve, a cam on the other end of said spindle, and adapted to be revolved therewith, a fuel pipe for said carbureter, a valve for said fuel pipe comprising a slidable non-rotatable interiorly threaded valve casing, a threaded 105 valve stem rotatably engaging said threaded valve casing and controlling the opening of said fuel pipe, a hand wheel on said valve stem, provided on its periphery with serrations, and a pivoted forked lever engaging at its forked end said valve casing, a reciprocating rod disposed between the opposite end of said lever and said cam, and having 110 contacting engagement therewith, and a spring on said valve casing adapted to maintain engagement of said cam, rod and forked lever, whereby the movement of said cam proportionately reciprocates said valve casing 115 and said valve stem, said valve stem adapted to be rotatably moved independently of said casing by movement of said hand wheel.

ently of said casing by movement of said hand wheel, and a spring indicator on said valve casing extending over said periphery of said hand wheel, and resiliently engaging between the serrations thereof to accurately determine the movement of said hand wheel, and retain the said hand wheel in position.

In testimony, that I claim the foregoing as my invention, I have signed my name in presence of two subscribing witnesses.

JOHN L. DRESSLER.
